SLIDER

John H. Kohler, Cambridge, Mass., assignor to
United-Carr Fastener Corporation, Cambridge,
Mass., a corporation of Massachusetts

Application June 25, 1940, Serial No. 342,241

5 Claims. (Cl. 24—205.5)

This invention relates to locking devices for separable fasteners of the slider-controlled type and has for its chief purpose to provide a pull device in assembly with the slider and constructed to engage automatically the separable fasteners upon release.

Referring to the drawing, in which I have illustrated a preferred embodiment of my invention:

Fig. 1 is a front view of my improved slider device showing parts thereof in locked position;

Fig. 2 is a sectional view taken along the line 2—2 of Fig. 1;

Fig. 3 is a section similar to Fig. 2 and showing parts of the slider device in unlocked position;

Fig. 4 is a front plan view of the pull member of my improved slider device;

Fig. 5 is a detail of the coil spring provided as a part of the device; and

Fig. 6 is a perspective of the pull member.

Referring to the drawing, I have shown a pair of stringers 1 and 2 provided with locking members 3 of any desired form adapted to be coupled and uncoupled by movement of a slider 4 along the stringers. The slider 4 has wings 5 and 6 forming diverging channels through which pass the locking members 3 while being engaged or disengaged by the slider. The slider has an attaching lug 7 formed in any suitable way and disposed on the outer face of the wing 5. The lug 7 has a recess 8 extending through the sides thereof. A pull member 9 is provided as a part of the slider having a longitudinal opening 10 (Fig. 4) spaced slightly from an end 11 to form a bridge intermediate the opening and end 11. The pull member has a slit 12 extending from the opening 10 through the bridge and cooperating with the opening 10 to divide the pull member into a pair of yieldable legs 13—13. At the same time the slit 12 divides the bridge into a pair of inwardly extending portions 14 and 15 for pivotal assembly within the opening 8 of the attaching lug. The pull member has an opening 16 extending laterally from the opening 10 adjacent the projection 15 for a purpose to be described. A projecting tongue 17 is formed integral with the pull member 9 adjacent its end 11 for engagement with the interlocking members 3 through an opening 18 (Figs. 2 and 3) of the wing 5 when the pull member is in inoperative position. The opening 18 is located in predetermined relation to the opening 8 of the attaching lug 7 to receive the tongue 17 of the pull member when the parts are in pivotal assembly.

The chief advantage of this invention is embodied in the construction of the slider enabling the tongue 17 to lock automatically with the locking members 3 when pressure upon the pull member for raising it into operative position is released. To accomplish this purpose I have provided a coil spring 19 having a body 20 (Fig. 5) which is generally cylindrical in form and providing free ends 21 and 22 extending outwardly in opposite directions. In assembling the parts 10 of the slider the coil spring 19 is disposed within the opening 8 of the attaching lug 7 with the end 21 engaging the outer surface 23 (Fig. 1) of the wing 5. Next the pull member 9 is pivotally attached to the attaching lug 7. Assembly 15 of the pull member with the lug 7 is preferably carried out by spreading the legs 13—13 to pass the free ends of the projections 14 and 15 over the ends of the body 20 of the spring and then closing the legs to dispose the free ends of the projections in substantially abutting relation within the body 20 and the opening 8 of the lug. The end 22 of the coil spring passes upwardly through the slot 16 of the pull member and is bent to engage the outer surface 24 of the pull member, as shown most clearly in Fig. 1. Thus in inoperative position of the member 9, as shown in Fig. 2, the tongue 17 engages between the locking members 3 so as to prevent movement of the locking members through the slider. When the pull member is grasped by the fingers and raised in operative position, as shown in Fig. 3, the tongue 17 is swung away from the locking members 3 into the opening 18 of the slider wing 5 so that the locking members may pass freely through the slider channels. Force upon the pull member to raise it into operative position is against the tension of the coil spring 19 with the result that when the pull member 40 is released, the coil spring automatically forces the pull member into inoperative position, shown in Fig. 2, so as to engage the tongue 17 with the locking members.

Thus by my invention I have provided a simple and advantageous method of effecting a locking action. My invention is an improvement over those slider devices heretofore known in which reliance was placed on the weight of the pull member to move it down into locked position due to the fact that with the present invention a positive action is automatically assured whereas with the earlier form it was usually necessary to deliberately push the pull member into inoperative position to be certain that the projecting

tongue thereof was in proper engagement with the locking members.

Although I have illustrated and described a preferred embodiment of my invention, I do not wish to be limited thereby because the scope of my invention is best defined by the following claims.

I claim:

1. The combination with a pair of stringers having interlocking elements thereon, of a slider movable along said stringers to control said interlocking members, said slider having wings forming diverging channels, an attaching lug on one of said wings having an opening, a pull member pivotally secured to said lug, said pull member having integrally inwardly-extending portions at one end projecting into said opening of said lug to pivot said pull to said lug, said pull member having a projection engageable with said interlocking members in inoperative position of said pull to lock said slider, and a spring assembled with said pull within said opening of said attaching lug, said spring being engageable with said slider and said pull member in all positions of the pivotal movement thereof to maintain automatically the pull in predetermined position upon the slider.

2. The combination with a pair of stringers having interlocking elements thereon, of a slider movable along said stringers to control said interlocking members, said slider having wings forming diverging channels, an attaching lug mounted on the outer surface of one of said wings, said lug having an opening, a pull member pivotally secured to said lug, said pull member having integral inwardly-extending portions at one end extending into said opening of said lug to pivot said pull to said lug, said pull member having a projection engageable with said interlocking members in down position of said pull to lock said slider, and a coil spring surrounding said inwardly-extending portions of said pull and disposed within said opening of said lug, said spring member having end elements engageable with said slider and said pull member in all positions of the pivotal movement thereof to maintain automatically said pull member in said down position.

3. The combination with a pair of stringers having interlocking elements thereon, of a slider movable along said stringers to control said interlocking members, said slider having wings forming diverging channels, an elongated attaching lug mounted on the outer surface of one of said wings, said lug having an opening, a pull

member pivotally secured to said lug, said pull member having integral inwardly-extending portions at one end extending into said opening of said lug to pivot said pull to said lug, said pull member having an opening adjacent said inwardly-extending portions to receive a portion of said lug when said pull member is in down position adjacent said last-mentioned wing, said pull member having a projection engageable with said interlocking members in said down position of said pull to lock said slider, and a coil spring surrounding said inwardly-extending portions of said pull and disposed within said opening of said lug, said spring member having end elements engageable with said slider and said pull member in all positions of the pivotal movement thereof to maintain automatically said pull member in said down position.

4. The combination with a pair of stringers having interlocking members thereof, of a slider movable along said stringers to control said interlocking members, said slider having wings forming diverging channels, an attaching lug on one of said wings having an opening, a pull member pivotally engageable with said attaching lug within said opening, said pull member having a projection engageable with said interlocking members in inoperative position of the pull member to lock the slider, and a spring member assembled with said slider within said opening of said attaching lug, said spring member being engageable with said slider and said pull member in all positions of the pivotal movement thereof tending to force said pull member into said inoperative position.

5. The combination with a pair of stringers having interlocking members thereon, of a slider movable along said stringers to control said interlocking members, said slider having wings forming diverging channels, an attaching lug on one of said wings having an opening, a pull member pivotally engageable with said attaching lug within said opening, said pull member having a projection engageable with said interlocking members in inoperative position of the pull member to lock the slider, a cylindrical coil spring disposed within said opening of said attaching lug, said pull member having portions disposed within said coil spring and said opening of said attaching lug, and said spring having end portions engageable with said pull member and said last-mentioned wing in all positions of the pivotal movement thereof tending to force said pull member into said inoperative position.

JOHN H. KOHLER.
